CARTRIDGE FEED-BELT FOR MACHINE GUNS

James A. Hendley, Middletown, Conn., assignor to The Russell Manufacturing Company, Middletown, Conn., a corporation of Connecticut

Application July 22, 1942, Serial No. 451,969

3 Claims. (Cl. 139—390)

This invention relates to improvements in woven cartridge feed-belts for machine guns.

One object of this invention is to provide an improved woven cartridge feed-belt for machine guns in which the cartridges carried by the belt have their projectile-ends housed or covered by a portion of the belt.

With the above and other objects in view, as will appear to those skilled in the art from the present disclosure, this invention includes all features in the said disclosure which are novel over the prior art.

In the accompanying drawings, in which certain ways of carrying out the invention are shown for illustrative purposes:

Fig. 1 is a fragmental elevational view of a portion of a cartridge feed-belt made in accordance with the present invention, and illustrating cartridges in some of the pockets thereof.

Fig. 2 is a sectional view on line 2—2 of Fig. 1;

Fig. 3 is an enlarged sectional view on line 3—3 of Fig. 1;

Fig. 4 is an enlarged sectional view on line 4—4 of Fig. 1;

Fig. 5 is an enlarged fragmental view of the weave construction;

Fig. 6 is an enlarged schematic cross-sectional view on line 6—6 of Fig. 1 illustrating the warp strands and their mode of crossing from one ply to the other;

Fig. 7 is a transverse schematic sectional view lengthwise of a pocket on line 7—7 of Fig. 1;

Fig. 8 is an elevational view similar to Fig. 1 of a modified construction;

Fig. 9 is a sectional view on line 9—9 of Fig. 8;

Fig. 10 is an elevational view of still another modified construction; and

Fig. 11 is an elevational view of still another modified construction.

In the following description and claims, the various parts and steps are identified by specific names for convenience, but they are intended to be generic in their application as the prior art will permit.

Referring to the form of the invention illustrated in Figs. 1 to 7 of the drawings, the cartridge feed-belt 20 has a series of cartridge-receiving pockets 21 extending transversely of the belt, each cartridge-receiving pocket 21 including a cartridge-gripping portion 22 adapted to cover and hold or grip an intermediate portion of a cartridge, and a projectile-end housing-portion 23 adapted to cover substantially all of the end of the projectile-end of the cartridge. The broken

line 24 in Fig. 1 indicates the junction-line of the portions 22 and 23.

The belt 20 is formed of two plies 25 and 26 formed by weaving a weft strand 27 with two sets of warp strands 28 and 29, each set of warp strands including pairs of warp strands 30 and single warp strands 31, the pairs of warp strands 30 being along the gripping-portion 22, and the single warp strands 31 being along the housing-portion 23. The weft picks of the weft strand 27 are woven as a continuous strand that goes back and forth from one ply to the other along the free edge 32 of the housing-portion 23.

Most of the pairs of warp strands 30 cross over back and forth from one ply to the other along the lines or regions 33 to form the large-diametered portion of the gripping-portion 22, while others of the pairs of warp strands 30 cross back and forth from ply to ply twice as often along the pairs of spaced-apart lines or regions 34 to form the small-diametered portion of the gripping-portion 22.

The single warp strands 31 cross back and forth from ply to ply along the same lines or regions 34 to form the housing-portion 23. Preferably, the single warp strands 31 are woven with the weft picks to form a looser woven portion of fabric than the pairs of warp strands 30 woven with the weft picks, thus providing a looser more-flexible weave for the housing-portion and avoiding tendency of the housing-portion to cramp or hinder the proper functioning or feeding action of the belt.

In the form of the invention illustrated in Figs. 8 and 9, the belt 20a is the same as the belt 20 illustrated in Figs. 1 to 7 with the exception that the housing-portion 23a has the same diameter as the larger part of the gripping-portion 22a.

In the form of the invention illustrated in Figs. 10, the belt 20b is the same as the belt 20 shown in Figs. 1 to 7 except that the gripping-portion 22b and the housing-portion 23b are all of the same size.

In the form of the invention illustrated in Fig. 11, the belt 20c is the same as the belt 20 of Figs. 1 to 7 except that the housing-portion 23c is formed of a series of different-diametered portions which provide a housing-space approaching the form of the end of the projectile to be housed therein.

Belts made in accordance with the present invention are preferably formed by weaving the warps with a single weft strand which crosses back and forth between the two plies of the belt, 55 to both form the weft picks of the plies of the

belt and close the end of the housing-portion which houses the projectile-end of the cartridge. It will thus be seen that belts made in accordance with the present invention can be manufactured on a single-shuttle loom.

By providing the housing-ports which cover substantially all of the end of the projectile-end of the cartridge, this end of the cartridge is protected from dirt and grit, so that as the cartridges are withdrawn from the belt and fed to the machine gun, the projectile-end of the cartridges will be substantially clean and thus minimize risk of interfering with proper functioning of the gun.

Where sets of warp strands are referred to, it does not mean that the same strands always form the same set, since, due to the crossing over from 15 ply to ply of warp strands, the identity of the warp strands forming the set in a ply will be different locations along the belt.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A cartridge feed-belt for machine guns comprising: a strip-like woven cartridge feed-belt having individual cartridge-receiving pockets extending transversely of the belt; each said pocket comprising a cartridge gripping-portion constructed and arranged to cover and hold an intermediate portion of a cartridge, and a projectile-end closed-end housing-portion constructed and arranged to cover substantially all of the end of the projectile-end of the cartridge, said

housing-portion being of a looser weave than said gripping-portion.

2. A cartridge feed-belt for machine guns comprising: two sets of warp strands woven with weft picks to form a strip-like two-ply cartridge feed-belt having individual cartridge-receiving pockets extending transversely of the belt; at least certain of the strands of each of said sets of warp strands crossing back and forth from one ply to the other to form said pockets; each said pocket comprising a cartridge gripping-portion constructed and arranged to cover and hold an intermediate portion of a cartridge, and a projectile-end closed-end housing-portion constructed and arranged to cover substantially all of the end of the projectile-end of the cartridge, said housing-portion having a lesser number of warp strands per unit of width than said gripping-portion.

3. A cartridge feed-belt for machine guns comprising: two sets of warp strands woven with weft picks to form a strip-like two-ply cartridge feed-belt having individual cartridge-receiving pockets extending transversely of the belt; at least certain of the strands of each of said sets of warp strands crossing back and forth from one ply to the other to form said pockets; each said pocket comprising a cartridge gripping-portion constructed and arranged to cover and hold an intermediate portion of a cartridge, and a projectile-end housing-portion constructed and arranged to cover substantially all of the end of the projectile-end of the cartridge, said housing-portion having a lesser number of warp strands per unit of width than said gripping-portion; and said weft picks having been woven as a weft strand periodically crossing back and forth from one ply to the other along the free edge of said housing-portion.

JAMES A. HENDLEY.
